CLAIM

The ornamental design for a portable scale with hinged expandable face, as shown and described.

DESCRIPTION

FIG. 1 is a top side perspective view of my new portable scale with hinged expandable face design

FIG. 2 is a top plan view of my new portable scale with hinged expandable face design

FIG. 3 is a bottom plan view of my new portable scale with hinged expandable face design

FIG. 4 is a front elevational view of my new portable scale with hinged expandable face design

FIG. 5 is a rear elevational view of my new portable scale with hinged expandable face design

FIG. 6 is a left side elevational view of my new portable scale with hinged expandable face design

FIG. 7 is a top side perspective view of my new portable scale with hinged expandable face design with the hinged display extended outwards in its “open” position

FIG. 8 is a top plan view of my new portable scale with hinged expandable face design with the hinged display extended outwards in its “open” position

FIG. 9 is a bottom plan view of my new portable scale with hinged expandable face design with the hinged display extended outwards in its “open” position; and,

FIG. 10 is a side perspective elevational view of my new portable scale with hinged expandable face design with the hinged display extended outwards in its “open” position.
